UNITED STATES PATENT OFFICE.

KURT WANDEL, OF NEW YORK, N. Y., ASSIGNOR TO INDUSTRIAL FOUNDATION, INC.,
OF BOSTON, MASSACHUSETTS, A CORPORATION OF MASSACHUSETTS.

PAPER-REENFORCING MACHINE.

Application filed March 6, 1920. Serial No. 363,713.

To all whom it may concern:

Be it known that I, KURT WANDEL, a citizen of Wurtemberg, who have declared my intention of becoming a citizen of the United States, and resident of New York city, county of New York, State of New York, have invented an Improvement in Paper-reenforcing Machines, of which the following description, in connection with the accompanying drawings, is a specification, like characters on the drawings representing like parts in each of the several views.

This invention relates to mechanism for applying reenforcing threads or filaments to a continuously moving web of paper or other sheet material in a manner so as to strengthen the web in all directions, but particularly transversely thereof. Various types of apparatus have hitherto been devised for this purpose and designed to lay the reenforcing threads crosswise of the paper web in a more or less diagonal direction, but all these prior types so far as known to me, that have been adapted to lay the threads at any practicable or commercial speed have involved the use of a rotary creel or spool carrier with the necessity of revolving a number of heavy spools of thread at a relatively high speed in order to lay the threads with the proper crosswise disposition and spacing on the moving paper web. This has in practice been a serious objection in the commercial production of reinforced paper where it is requisite that the paper web be advanced at the rate of one hundred feet per minute and upward, the present day requirements demanding a speed even very much greater than this. A principal object of the present invention is to provide thread laying apparatus adapted for co-operation with a moving paper web wherein the thread spools are stationarily mounted, and the only moving instrumentality of the thread laying mechanism is the immediate thread laying means which applies the threads in diagonal crossed relation to the moving paper web and is preferably located closely adjacent to the "bite" between a pair of press rolls which unite the filaments to the paper surface which is usually pregummed or treated with suitable adhesive. As herein shown, the apparatus is associated and combined with a paper duplexing mechanism and the product produced is a composite reinforced paper web,

although in a broader aspect the invention is not to be understood as limited to this combination. The foregoing and other objects and advantages of the invention will more fully appear from the following detailed description, and the distinctive features of novelty will thereafter be pointed out in the appended claims.

Referring to the drawings:

Fig. 1 is a side elevation showing apparatus embodying the invention;

Fig. 2 is a plan view thereof;

Fig. 3 is a view partly in transverse section, and partly in elevation with portions broken away showing the immediate thread laying instrumentality;

Fig. 4 is a plan view of the part of the apparatus shown in Fig. 3;

Fig. 5 is a partial elevation on an enlarged scale showing a part of the thread laying means;

Fig. 6 is a transverse section thereof;

Fig. 7 is a partial plan view of the thread laying means; and,

Fig. 8 is a fragmentary perspective view showing a part of the track in which the thread laying means moves.

10, 11, indicate a pair of press rolls, around and into the bite of which are led paper webs W, W', from paper supply rolls R, R', respectively. One of these webs, as shown, the web W is led through a coating station where suitable adhesive which may be hot asphalt or glue, or other suitable substance, is applied to the web by a transfer roll 12 from a tank or pan 13 in which such roll is partly immersed. 14 indicates a stand constituting a mounting for a series of thread spools S from which the series of reenforcing filaments F is drawn. A thread guide and alining plate 15 may be mounted on uprights 16 so as to be at approximately the elevation of the mouth or bite between the rolls 10, 11. This plate is equipped with a series of thread guiding apertures 15^a corresponding in number to the number of threads or filaments to be handled and with these apertures equally spaced apart throughout the length of said plate. A stand 17 on which the rolls 10, 11, may also be mounted as shown, is equipped with an undercut or T-slot 18 extending lengthwise of the rolls and directly in front thereof, this slot affording means whereby uprights 18, 19, may be adjustably clamped to

said stand by means of T-headed bolts 20. These uprights which may thus be spaced apart according to the width of paper web being handled, serve as supports for the ends of a track 21 in which the thread laying device is mounted for movement. This track is of channel iron form with inturned flanges 210^a constituting a channel of T-shaped cross section which retains 10 the thread laying device therein throughout its travel. The thread laying instrumentality is of a flexible character capable of following the curved path of the track 21 as presently described, and this thread laying 15 means may consist in a chain 22, each link 22^a of which may be composed of a plurality of plate members arranged in alternating and over-lapping relation with the corresponding members of the next link. These 20 over-lapping link portions may be secured together by tubular studs 23 which constitute guides for certain of the threads which are passed therethrough. The intermediate portion of the links between these pivots 25 may be formed with a series of passages 24 therethrough for other threads, the spacing of these passages with respect to one another and with respect to the passages through the pivot studs 23 being determined by the 30 desired spacing of the filaments to be laid. These links are formed with lugs or projections 23^a, 23^b at top and bottom thereof which bear pivot pins 25 for rolls 26, 27, which are disposed at each side of each link 35 at top and bottom thereof, these rolls being adapted to engage in the channel of the track 21 resting on the flanges 210^a thereof. The link projections 23^a, 23^b, are rounded and spaced apart so as to co-operate with 40 a sprocket chain 260 the teeth 260^a of which are adapted to fit in between these link projections. Upper and lower horizontal stretches 21^a, 21^b of the track 21 have the intermediate back or outer portion of the 45 track cut away as indicated at 270 so that the sprocket chain 260 may extend therethrough to engage the link projections of the thread laying chain. The track 21 is composed of two portions 21^c and 21^d which 50 together constitute a flattened figure 8 and as now to be described together make a continuous runway for the thread laying chain. The track portion 21^c is composed of two 55 flat parallel stretches, 21^c already referred to, and 21^e between which at one side is a curving semi-circular portion 21^f. The flat stretch 21^c of the track extends alongside of and directly over a similar flat stretch 21^g of the track part 21^d, and the portions 21^b, 60 21^g, of the track part 21^d are joined at one side by a semi-circular portion 21^h similar to the portion 21^f already mentioned. At the other side of the track the portions 21^b, 21^g, are curved inward towards each other 65 in portions 21ⁱ, 21^k, the extremities of these

portions being relatively displaced laterally and over-lapping by slightly less than one-half the width of the thread laying chain, as indicated at 21^l, 21^m. The extremities of the stretches 21^c, 21^g, extend to points adjacent 70 to the extremities 21^l, 21^m, respectively, as indicated at 21ⁿ, 21°. The extremities 21^m, 21° are arranged in the same vertical plane, with the extremity 21° radially inward from the extremity 21^m, and the extremities 21^l, 21ⁿ 75 are likewise in the same vertical plane at one side of the extremities 21^m, 21°, with the extremity 21ⁿ radially inward with respect to the extremity 21^l. The length of the thread laying chain 22, such that when its advance end 22^b,—assuming it to be moving in the direction of the arrow Fig. 3,—reaches the crossover from the extremity 21^m to the extremity 21°, the rear end 22^c thereof has passed the crossover 21^l, 21ⁿ, in 80 its travel along the stretch 21^c, and a similar condition exists when the advance end 22^b makes the crossover from the extremity 21^l to the extremity 21ⁿ, i. e., at that time the rear end 22^c has passed the crossover 21^m, 21°. This is necessary in order that there shall be no interference of the threads at the crossover, it being understood that there is enough space between the co-operative track extremities 21^l, 21ⁿ, and 21^m, 21^o, so 85 that the line of threads may pass therethrough when the rolls of the thread laying chain are transferred from one track extremity to the other as now to be explained. While the thread laying chain is travelling along the track stretches 21^a, 21^b, the upper line of rolls 26 engages with the track, and just as this line of rolls runs off the extremity 21^m, the other or inner line of rolls 27 catches into the track extremity 21° continuing thus until the line of rolls 27 runs 90 out of the track extremity 21^l just after the other line of rolls 26 is caught by the track extremity 21^a. In this way it will be noted that the filaments which are held by the 95 thread laying chain portion borne by the track stretch 21^a (as seen in Fig. 3) will be drawn diagonally across the moving paper web in one direction, while the filaments that are held by the thread laying chain portion at the track stretch 21^c are being 100 drawn diagonally in the opposite direction. Then as the advance end 22^b of the thread laying chain progresses along the track stretch 21^c the threads borne thereby complement and continue the line of threads that leave off with the rear end 22^c. Thus 105 throughout the operative movement of the thread laying chain in its figure 8 track, two lines of diagonal and intersecting 110 threads will be supplied to the bite or mouth between the presser rolls 10, 11. Since the described thread laying device is located relatively close to the press rolls, the 115 successive diagonal threads as they reach 120

the edge portions of the web are caught by the bite between the rolls so that as the thread laying chain starts the thread on its return movement it will be drawn diagonally from one edge of the web to the other alternately. This mechanism for laying the threads will, it will be observed, cause a partial twisting of the threads between the thread laying chain and the guide plate 15 5 in each direction, which will however be righted on the next succeeding stretch of the chain movement so that no twisting or tangling of the threads can occur and the proper continuous feed thereof from the stationary spools is insured. In order to insure that the threads on passing the crossovers as described shall not catch on the ends of the track sections, these sections may have their edges slightly beveled as indicated at α in Fig. 8. The chain 260 which has been described as engaging the thread laying chain 22 to operate the same in the outer track stretch 21^a is mounted on an idle sprocket wheel 28 journaled in a bearing 29 10 on the upright 19 and on a driving sprocket wheel 30 journaled on a bearing 31 borne by the other upright 18. The sprocket wheel 30 is shown as driven by a belt and pulley connection 32 from a suitable driving motor 33. Since this chain 260 can only drive the thread laying chain while a portion thereof is in the track stretch 21^a, it is requisite to provide another similar chain 34 to engage the thread laying chain 22 15 at the track stretch 21^b, this insuring the continuous driving of the thread laying chain since some portion thereof is always in one of the track stretches 21^a or 21^b. The chain 34 is mounted on a driving sprocket wheel 35 operated by spur gears 36 from the wheel 30 and in unison therewith, and around a second idler sprocket wheel 37 journaled alongside the sprocket wheel 38. For different widths of paper webs the uprights 18, 19, may be set at varying distances apart, and the required number of links added to, or taken from, the thread laying chain 22 and the driving sprocket chains so as to make the required length 20 thereof, and the track 21 may either have sections inserted or removed, or be replaced by other track portions of different widths according to requirements. The duplex web W² reinforced by the crisscross diagonal 25 filaments laid as described and embedded in the cementitious binder between the plies of the paper, may be led onto a take-on roll R² or otherwise taken care of. While I show herein the crossover between the track 30 sections at one side of the figure 8 track, this particular location of the crossover is merely illustrative and preferred, and the invention is not to be understood as limited in this respect. In this as well as other 35 particulars and details the present embodiment

is to be considered as illustrative and not restrictive, reference being had to the appended claims rather than to the foregoing description to indicate the scope of the invention.

Having described my invention, what I claim as new and desire to secure by Letters Patent is:

1. Apparatus of the kind described, comprising means for continuously advancing a paper web, a relatively stationary source of thread supply, and means operable in a closed circuitous path for continuously moving threads from such thread supply towards opposite edges of the paper web alternately.

2. Apparatus of the kind described, comprising a pair of press rolls having means associated therewith for delivering thereto two paper webs to be duplexed, a relatively stationary source of thread supply, and a continuously moving thread carrier constructed and arranged to deliver the threads continuously to the bite between said rolls in crisscross relation.

3. Apparatus for making reinforced paper, comprising means for continuously advancing a paper web including a press roll, a relatively stationary source of thread supply, and continuously moving means operable in a closed circuitous path mounted adjacent said roll and bearing the threads from such supply constructed and arranged to deliver the threads upon the paper web transversely thereof.

4. Apparatus for making reinforced paper, comprising means for continuously advancing a paper web including a press roll, a relatively stationary source of thread supply, and means mounted to move in an endless path for guiding the threads transversely of the paper web and alternately towards opposite sides thereof.

5. Apparatus for making reinforced paper, comprising means for continuously advancing a paper web including a press roll, a relatively stationary source of thread supply, and means mounted to move in an endless path equipped with thread guides and constructed and arranged to draw the threads diagonally of the paper web in crisscross relation continuously.

6. Apparatus for making reinforced paper, comprising paper handling mechanism including a press roll, a source of thread supply, and flexible thread guiding means constructed and arranged for continuous movement in an endless path, parts of which intersect other parts, for continuously laying threads upon the moving paper in diagonal transverse relation thereto.

7. Apparatus for making reinforced paper, comprising paper advancing means including a press roll, and thread laying means mounted adjacent said roll and con-

sisting in a thread carrier mounted for continuous movement in an endless path, portions of which intersect other portions, and being adapted to draw the thread diagonally 6 of the moving web alternately towards opposite sides thereof.

8. Apparatus for making reinforced paper, comprising means for advancing a

paper web including a press roll, a stationary source of thread supply, and a thread carrier mounted adjacent said press roll for movement in an endless path of flattened figure 8 outline. 10

In testimony whereof, I have signed my name to this specification.

KURT WANDEL.
